UNITED STATES PATENT OFFICE.

SAMUEL HENRY OWENS, OF EVELETH, MINNESOTA.

CARD-HOLDER.

SPECIFICATION forming part of Letters Patent No. 735,802, dated August 11, 1903.

Application filed March 2, 1903. Serial No. 145,634. (No model.)

To all whom it may concern:

Be it known that I, SAMUEL HENRY OWENS, a citizen of the United States, residing at Eveleth, in the county of St. Louis, State of Minnesota, have invented certain new and useful Improvements in Card-Holders; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a card-holder adapted to be attached to railway-cars; and it consists in the construction and arrangement of parts hereinafter fully set forth, and pointed out particularly in the claims.

20 The object of the invention is to provide simple and efficient means for fastening the tags or cards to railway-cars without the use of tacks or similar fastening means, the arrangement being such as to readily enable the 25 card to be inserted in the holder and easily removed therefrom.

The above object is attained by the structure illustrated in the accompanying drawings, in which—

30 Figure 1 is a perspective view of this improved card-holder mounted on a car, the body of the car being broken away. Fig. 2 is a section, as on line 2 2 of Fig. 1. Fig. 3 is a plan view of the hinged member of the 35 holder. Fig. 4 is an end view of the base upon which the hinged member is mounted.

Referring to the characters of reference, 1 designates a suitable base adapted to be secured to the car by bolts or any other means.

40 In the rear face of said base is a channel 2, extending horizontally across it, and formed upon the front face of said base is a shoulder 3.

The hinged member of the holder consists of a transverse bar 4, adapted to lie in the 45 channel 2 in the rear face of the base and having right-angle side portions 5, adapted to lie on each side of said base. From the side portions 5 of said bar extend the angular end portions 6, which are secured in the cross-bar 7, that extends transversely across the

face of the base and when in its normal position is adapted to swing under the shoulder 3. From the cross-bar 7 the arms 8 project parallel with the face of the base. In the outer ends of the arms 8 are secured the inwardly-projecting brads or pins 9. These brads, as will be seen, are of greater diameter near their outer ends and taper toward their point of attachment to the arms 8. The arms 8 may be secured in the cross-bars 7 by 55 means of screws 10, as shown, or said arms may be cast integral with said cross-bar and with the hinged member 4.

In placing the holder upon the base the cross-bar 4 is allowed to enter the channel 2 65 in the back of the base, when the bar 7 will stand across the face of the base and normally lie under the shoulder 3. When the holder is so mounted on the base and the base secured to the car, said holder becomes 70 hinged to the base and may be swung outwardly, as shown by dotted lines in Fig. 2.

When it is desired to place a card in the holder, the bar 7 is swung outwardly by grasping the knob 11 at the end thereof and the 75 card 12 is shoved upwardly against the outer face of the base until it strikes the shoulder 3, when the cross-bar is swung downwardly, causing the brads 9 to pass through the card and enter the apertures 13 in the base, whereby the card is firmly held in place. As an additional means for securing the card a brad 14 is secured to the center of the bars 7, which is adapted to engage the top of the card, as shown in Fig. 2, and to lie in the aperture 15, formed in the base. 80

It will be noted that the holder-frame carrying the brads is so mounted on the base as to stand at one side of the center of gravity through the point of hinging of said frame. 90 By this arrangement there is present a constant tendency of the hinged frame to swing inwardly against the base, thereby maintaining it in a closed position and assuring a retention of the card. When the hinged frame 95 is released after being raised, it will swing downwardly by force of gravity and by its own weight will hold itself closed.

The taper of the brads 9 is such as to cause the torn margin of the card through which 100

they pass to close around the small diameter of the brads after they have been forced through the card and prevent the withdrawal of the card from the brads except by the exercise of considerable force.

The lower edge of the base is recessed, as at 16, to facilitate the insertion and removal of the card when required.

Having thus fully set forth this invention, to what I claim as new, and desire to secure by Letters Patent, is—

1. In a card-holder, the combination of a base, a frame hinged to the base and weighted to swing downwardly by gravity to confine a card thereon, brads mounted upon said frame adapted to pass through a card, said brads being of greater diameter near their points and tapering toward the support in which

they are mounted to prevent the card from slipping therefrom.

2. In a card-holder, the combination of a base having a channel in the rear face thereof, a holder-frame having a transverse bar adapted to lie in said channel and rotate therein to form a hinge, a second bar crossing the face of the base and attached to the hinged bar, arms projecting from said second bar, perforating-brads in the ends of said arms, and the base having recesses adapted to receive said brads.

In testimony whereof I sign this specification in the presence of two witnesses.

SAMUEL HENRY OWENS.
